DESCRIPTION

Jul. 28, 1999 (KR) 99-17910
(51) LOC (7) Cl. **13-03**
(52) U.S. Cl. **D13/182**
(58) Field of Search D13/182; 361/380,
361/384, 352, 395, 397, 398

FIG. 1 is a perspective view of a board of wireless frequency
for amplification of transmitting and receiving electric wave;
FIG. 2 is a plan view thereof;
FIG. 3 is a bottom view thereof;
FIG. 4 is a left side view thereof;
FIG. 5 is a right side view thereof; and,
FIG. 6 is a front view thereof.
